(57) **CLAIM**

The ornamental design for a sensory board, as shown and described.

DESCRIPTION

FIG. 1 is a perspective view of a sensory board according to the invention;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The ornamental design which is claimed is shown in solid lines in the drawings. Features shown in broken lines are presented for illustrative purposes and form no part of the claimed design. The pair of unshaded inner rectangular surfaces in FIG. 2 form no part of the claimed design.

1 Claim, 5 Drawing Sheets
